J. Tiberi

Crane.

No. 288.

A. S. Patented July 17, 1860.

Witnesses;
Amos Stevens
Henry

Inventor;
Joseph Tiberi

Tibers Patent No. 25,352.—Improvement in Grates.—I claim the combination of a back E, with the stationary back B, when they are arranged with the flue T behind them and under the grate, in the manner shown.

JOSEPH TIBERI.